UNITED STATES PATENT OFFICE

BANCROFT G. BRAINE, OF NEW YORK, N. Y., ASSIGNOR TO THE RAIL JOINT COMPANY,
OF NEW YORK, N. Y., A CORPORATION OF NEW YORK.

EQUALIZED RAIL-JOINT.

1,246,861.

Specification of Letters Patent. Patented Nov. 20, 1917.

Application filed March 27, 1916. Serial No. 87,039.

To all whom it may concern:

Be it known that I, BANCROFT G. BRAINE, a citizen of the United States, residing at New York city, in the county of New York and State of New York, have invented certain new and useful Improvements in Equalized Rail-Joints, of which the following is a specification.

This invention relates to an improvement in rail joints and has for its object a novel arrangement and combination of the joint parts to more nearly equalize the bending stresses imposed by wheel-loads.

In the average rail joint the joint bars are not in such equilibrium with the rail as to obtain a uniform distribution of the loading strains, and it is, therefore, the purpose of the present invention to correct this condition, to a very substantial and practical degree, by so disposing the joint bars with reference to each other and to the rail as to equalize the effect of the differences in location of the neutral axes of the bars and of the rail, thereby enabling the joint to withstand, uniformly, the upward and downward stresses imposed by wheel-loads.

With the foregoing practical object in view, the invention consists in the novel relation of joint parts, hereinafter more fully described, illustrated and claimed.

Though susceptible of embodiment in various types of rail joints, and with various forms of rail-splices, certain preferred and practical embodiments of the invention are shown in the accompanying drawings, in which—

Figure 1 is a perspective view of a simple form of angle bar rail joint constructed in accordance with the present invention.

Fig. 2 is a cross-sectional view of the joint shown in Fig. 1.

Like references designate corresponding parts in the several figures of the drawings.

The distinctive feature of the present invention is such an arrangement of a pair of opposite joint bars, of the same uniform section, that the mean of their respective neutral axes will be centralized and made to

correspond, approximately with the neutral axis of the rail. For instance, as best seen in Fig. 2 of the drawings, the numerals 1 and 2 designate the opposite joint bars of a rail joint. As shown these two joint bars are duplicates in design and section, but one bar occupies an inverted position, so that the said opposite bars are reversely related. The effect of this reversal, in the relation of the opposite bars in the joint, is to centralize the mean of their respective neutral axes. To illustrate this, the joint bars, having the section of the bars 1 and 2 illustrated in the drawings, will have their neutral axes disposed, respectively, below and above the horizontal center line of the fishing spaces of the rails. In Fig. 2 of the drawings the horizontal neutral axis of the bar 1 is designated by the line 1 N. A., which lies below the center line C. L. of the fishing space of the rails, and the horizontal neutral axis of the bar 2 is designated by the line 2 N. A., which lies above the center line C. L. of the fishing space of the rail. The said neutral axes of the bars 1 and 2, on account of the uniform section of the latter, are disposed at substantially equal distances from the center line of the fishing spaces, so that the relative reversed relation of the two bars serves to centralize the mean of their neutral axes to make it correspond, approximately, with the neutral axis of the rail, which usually lies adjacent the center line of the fishing space. It is by reason of this feature that the present invention accomplishes the object referred to.

From the foregoing, it is thought that the construction and the important advantages of the improvement in rail joints will be apparent without further description.

I claim:

1. A rail joint including a joint bar unsymmetrical about its vertical and horizontal axes, and an opposite inverted bar of the same section.

2. A rail joint including opposite angle bars, one of said bars being inverted.

3. A rail joint including the rail and a pair

of opposite unsymmetrical bars of the same section and one of which bars is inverted to thereby cause the mean of the neutral axes of the two bars to correspond approximately with the neutral axis of the rail.

4. A rail joint including opposite unsymmetrical joint bars of similar section having their horizontal neutral axes disposed respectively above and below, and at sub-

stantially equal distances from, the horizontal center line of the fishing spaces. 10

In testimony whereof I hereunto affix my signature in the presence of two witnesses.

BANCROFT G. BRAINE.
